Chas. H. Fowler,

UNITED STATES PATENT OFFICE.

THOMAS SIMMONS, OF HARTFORD, CONNECTICUT.

TRUSS.

SPECIFICATION forming part of Letters Patent No. 374,091, dated November 29, 1887.

Application filed July 5, 1887. Serial No. 243,416. (Model.)

To all whom it may concern:

Be it known that I, THOMAS SIMMONS, a citizen of the United States, residing at Hartford, in the county of Hartford and State of Connecticut, have invented certain new and useful Improvements in Trusses; and I do hereby declare that the following is a full, clear, and exact description of the same, reference being had to the annexed drawings, making a part of this specification, and to the letters and figures of reference marked thereon.

Figure 1 of the drawings is a perspective view of my improved truss; Fig. 2, a sectional view, in detail, of that end of the truss provided with pawl and ratchet; Fig. 3, a detail plan view of that portion of the truss provided with a back spring, and Fig. 4 an edge view of Fig. 3.

The object of the present invention is to provide a simple and easily-adjusted truss that may be reversed at pleasure and adjusted to give ease and comfort to the wearer; and it consists in the details of construction, substantially as shown in the drawings, and hereinafter described and claimed.

The truss consists of the usual flexible band, A, provided at one end with a leather or other suitable tongue or strap, B, having holes a, to engage with buttons or other suitable fastenings on the metal plate C, so as to adapt the band to the requirements of the person wearing it. The band A may be formed of any suitable material found best adapted to the purpose, and is provided with pads D, also of any preferred construction.

The plate C is formed of spring metal, so as to provide a spring-plate, to the inner side of which is secured a suitable cushion, E. To the widest end of the plate C is secured in any suitable manner the pad F; also, to said plate is connected in any well-known manner a bracket, b, in which is located a ratchet-wheel, c, with which engages a spring-pawl, d. This ratchet-wheel is formed integral upon the end of a short shaft or coupling-section, G, which has its bearing in the side of the bracket b, said coupling-section being pivoted in any well-known manner to an extension, H, of a metal plate or band, I, said plate having the usual lining, e, upon the inner side thereof. The opposite end of the

plate I is pivotally connected to the flexible band A, as shown more clearly in Fig. 3, and is provided upon its outer side with a spring, K. The metal band I is also formed of spring metal, so as to act as a spring, and may be of any suitable length and width, as found best adapted to the purpose; and I do not desire to be understood as limiting myself to any special form of flexible band or form or construction of pads, as they may be modified in form, so long as it comes within ordinary mechanical skill and may be constructed of any desirable material, and any number of pads may be used and located upon the truss with relation to each other as circumstances may require.

By means of the pawl-and-ratchet connection the truss can be adapted for use, either for right or left hernia, by simply reversing the ratchet; and it is also adapted for use in cases of double hernia, as well as for single hernia, and when to be used for the former a suitable pad is connected to the plate C by means of screw f, or other suitable fastening.

The spring K is connected to the spring-band I at one end by means of a suitable rivet, g, and its opposite end is slotted, as shown at h, and is unattached to the spring-band and free to act. A screw, i, passes through the slot h of the spring and through the band I, as shown in Fig. 4, and by adjusting said screw it will bear with greater or less force upon the band I, and after the band has been manipulated to fit the body snugly the screw, as hereinbefore described, is adjusted so as to cause a back action on the band by the pressure of the spring K, and by that means remove from spinal column a pressure which with ordinary spring attachments is a cause of considerable injury to persons obliged to wear such mechanical appliances.

The pads D save the spine from irritation, and the general construction of the truss gives comfort to the wearer, and may be adjusted to adapt itself to circumstances.

Having now fully described my invention, what I claim as new, and desire to secure by Letters Patent, is—

1. In a truss, the combination, with the plate C and the pad carried thereby, of the bracket b, secured to said plate, the pawl d, the coupling-section G, and the ratchet-wheel

formed integral with said section, journaled in said bracket and engaging said pawl, substantially as described.

2. In a truss, the combination, with the metal band I, of the metal spring K, secured at one end to said band and slotted at its other end, and the set-screw i, passed through the slot of the spring and through the band I, substantially as shown and described, and for the purpose specified.

In testimony that I claim the above I have hereunto subscribed my name in the presence of two witnesses.

THOMAS SIMMONS.
